X-RAY FILM PROCESSING TANK

Leonard W. Gacki, White Plains, N.Y., assignor to
Medical Metals Incorporated, a corporation of New
York

Filed Feb. 19, 1962, Ser. No. 68,993

Term of patent 14 years

(Cl. D61—1)

Fig. 1.

Fig. 2.

Fig. 3.

Fig. 4.

FIG. 1 is a front perspective view of an X-ray film processing tank showing my new design;

FIG. 2 is a front elevational view thereof;

FIG. 3 is a right-side elevational view thereof; and

FIG. 4 is a top plan view thereof.

The rear of the tank, not shown, is substantially plain and unornamented.

I claim:

The ornamental design for an X-ray film processing tank, as shown and described.
